UNITED STATES PATENT OFFICE.

LEE R. MOTHERWELL, OF PEORIA, ILLINOIS, ASSIGNOR TO CULTER & PROCTOR STOVE CO., OF PEORIA, ILLINOIS.

STOVE OR RANGE.

1,325,106.

Specification of Letters Patent.

Patented Dec. 16, 1919.

Application filed September 22, 1916. Serial No. 121,540.

To all whom it may concern:

Be it known that I, LEE R. MOTHERWELL, a citizen of the United States, residing at Peoria, in the county of Peoria and State of Illinois, have invented new and useful Improvements in Stoves or Ranges, of which the following is a specification.

This invention has reference to certain new and useful improvements in stoves or ranges, and particularly to that type of such stoves or ranges wherein either solid fuel or gas may be burned, as desired.

One of the objects of the present invention is to so construct the stove or range for use with solid fuel or gas, that either one or both may be used separately or simultaneously without the addition of any parts, or the removal of any parts.

The invention has for a further object to provide a valve controlling the supply of gas to the oven burner, and a valve controlling the discharge of the gas or products of combustion from the oven into the chimney or flue, and an operating means connecting both of said valves, whereby, when the valve controlling the gas to the burner is opened or closed, the valve controlling the discharge of the products of combustion is simultaneously opened and closed.

The invention has for a further object to improve the burner construction for the oven and the walls of said oven, so as to provide proper channels for the inlet of the air to mix with the gas, and courses of travel of the products of combustion to uniformly heat the oven in the passage of the products of combustion from the burner to the flue of said stove or range.

A further object of the invention is to so construct the main bottom of the stove or range, and its supplemental bottom up through which the products of combustion pass, when the gas burner is used, that said supplemental bottom will be in the same plane with the surface of the oven door when said door is in its open or flat position.

A further object of the invention is to locate the burners for the stove or range at the opposite sides of the oven and to provide a supplemental oven bottom which is perforated approximately centrally thereof to insure the travel of the products of combustion centrally of the oven in their passage to

the flue through which said products of combustion escape; and also in the provision of a supplemental rear oven wall open only at its lower edge and under which the products of combustion must travel in their passage to the flue.

The annexed drawings and the following description set forth in detail certain means embodying my invention, the disclosed means, however, constituting but one of various mechanical forms in which the principle of the invention may be applied.

In said annexed drawings:

Figure 1 is a plan view, in section, of my improved stove or range, as the same would appear if taken on the line B—B of Fig. 2;

Fig. 2 is a front vertical sectional view of my improved stove or range, parts broken away;

Fig. 3 is a vertical transverse sectional view of my improved stove or range, as the same would appear if taken on the line A—A of Fig. 1, and

Fig. 4 is a perspective view of one of the supplemental side walls, or linings, for the sides of the oven.

Like characters of reference denote corresponding parts throughout the figures.

I have shown the stove or range supported on the usual legs 1, and having the fire-box 2, the ash-pit 3 therebeneath, the oven 4 and flue 5 for the escape of the products of combustion to the chimney with which said flue 5 may be connected. Communicating with the fire-box 2 is a flue or chamber 6 which overlies the oven 4, and said flue or chamber 6 communicates with a flue or chamber 7 on the far side of the oven, and this flue or chamber 7 communicates with a flue or chamber 8 underlying the oven 4, and oven bottom 9. The last mentioned flue or chamber 8 communicates with the flue 5 at its lower end. To insure the products of combustion from the fire-box 2 covering the whole area of the oven bottom 9, there is a baffle-plate 10 extending toward the center of the oven from the wall of the flue 5 nearest the center of the stove or range, see Fig. 1.

The description thus far has to do with the construction of the stove or range when coal or other solid fuel is used to heat the oven 4. The flues or chambers 6, 7 and 8

present a heating surface which insures the uniform heating of the oven walls, and is substantially that construction to be found in stoves or ranges in general use, except that the bottom wall 9 of the oven has been lowered so as to bring the surface of the supplemental oven bottom 11 on the same plane with the surface of the oven door 12 when it is in the open position, shown in Fig. 3.

The supplemental oven bottom 11 is adapted to be removed from the oven, being supported on flanges 13 extending inwardly from the lower edge of linings 14 located at either side of the oven 4. These linings 14 are spaced inwardly from the side walls of the oven to provide flues or chambers 15, and in height extend only part way up in the oven, see Fig. 2, and the lower edges of said linings are raised above the bottom 9 of the oven to provide communication between the flues or chambers 15 and a flue or chamber 16 provided between the supplemental bottom 11 and the bottom 9. The linings 14 have a front wall 17 to close the front of the flue or chamber 15, and in the lower end of said front wall 17 an opening 18 is provided, for a purpose to be explained; said linings 14 are further provided with laterally extended lugs 19 serving as a support for a shelf or plate 20, and slotted openings 21 in said linings serve a purpose to be explained.

22 designates a burner, including the main pipe 23 disposed along the lower portion of the rear wall of the oven, and the right angle pipe extensions 24 disposed along the lower portion of the side walls of the oven. The extensions 24 of the burner represent the active portions of the burner, and are provided with openings 25 in their upper walls, from which a gas-flame may issue in a vertical direction in the flues or chambers 15, and 26 are openings similar to the openings 25 and are for the same purpose, except the openings 26 are disposed diagonally in the burner, preferably in the lower portions thereof so that the gas flame will issue in the direction of the flue or chamber 16 beneath the supplemental oven bottom 11. The transverse hollow member 23 which connects the two burner extensions 24 thus serves as means for equalizing the flow of gas or evenly distributing the flow to the burner extensions. Leading into the rear of the stove or range and connected to the main burner pipe 22 is a supply pipe 27, leading to a suitable source of supply. To provide for a proper mixture of oxygen and gas, in the oven, I provide flues 28 along the lower portions of the side walls of the oven which open out of the rear wall of the stove or range as at 28^a, and in the side walls of the stove or range, at or near the top of the pipes 24 of the burner and at or near the

bottom of the pipes of said burner, I provide a row of openings 29 for the egress of air from the flues 28 into the flues 15.

30 designates a lining for the rear of the oven and is spaced from the rear wall of the stove or range approximately the same distance as the supplemental bottom 11 for the oven is spaced from the bottom 9, providing a chamber 31. The lining 30 is removable from the oven, and when in place the lower edge of said lining is spaced slightly above the pipe 22 of the burner to provide an opening 32 through which the products of combustion may escape from the oven into the flue 5. Such escape is through an opening 33 in the rear wall of the stove or range, into the flue. The opening 33 is controlled, preferably by a slide valve 34. This valve has an arm 35 having a series of openings 36, by means of which an adjustable connection may be made between said arm and a link 37, by a bolt 38. The opposite end of the link has a pivotal connection with a crank arm 39 connected with a rod or stem 40 disposed on the rear side of the stove or range, and its lower end connected with a valve 41 arranged in the supply pipe 27. On the upper end of the rod or stem 40 is an operator's handle or lever 42 for operating said rod or stem 40. The connections between the rod or stem 40 and the valve 34, and the rod or stem 40 and said valve 41 are such that when the valve 41 is opened to permit the gas to flow from its source of supply to the burner, the valve 34 is opened, and when the valve 41 is closed, the valve 34 will be simultaneously closed. To increase or decrease the draft through the flue 5 it is only necessary to change the point of connection between the link 37 and the arm 35 of the valve, whereby it may be moved more or less, as desired, when the rod or stem 40 is operated.

To insure the products of combustion from the burner passing to the center of the oven and uniformly baking whatever may be in the oven, I perforate only the central portion of the supplemental oven bottom 11, see Fig. 1, by providing the perforations 43. With this provision the products of combustion below the supplemental oven bottom cannot rise until at or near the center of the oven, insuring a uniform radiation of the heat, as will become more fully apparent.

I have described the travel of the products of combustion from a solid fuel in the fire box 2 and its escape into the flue 5. It is obvious from the foregoing description of parts that solid fuel or gas may be used to heat the oven, and used independently of each other, or at the same time, as may be desired.

I will now describe the travel of the products of combustion from the burner 22, when gas is used, through the oven into the flue 5.

The stem 40 is operated to release the gas to the burner 22, and at the same time the valve 34 is moved to open the exit 33 through which the products of combustion will escape 5 into the flue 5, and the opening of which will provide the necessary draft to draw the products of combustion from the oven. Upon turning on the gas, a lighted match inserted into the openings 18 of the linings 10 14 will cause the gas escaping through the openings 25 and 26 in the pipe sections 24 of the burner to become ignited, a proper combustion taking place, by the admission of the required amount of air taken into the 15 flues 28 and admitted to the burner chambers through the openings 29 communicating with the flues 28. The products of combustion from the flame at the openings 26 in the burner will traverse the flue or chamber 20 16 beneath the supplemental oven bottom 11 until the openings 43 located centrally thereof are reached when the same will ascend through such openings. The 25 products of combustion from the flame at the openings 25 in the upper wall of the burner sections 24 will rise in the flue or chambers 15, part passing into the oven proper through the openings 21 in the linings 14 and the remainder passing up over 30 the upper edge of said linings 14, into the oven proper. The exit for the products of combustion being through the opening 32 below the lower edge of the rear lining 30 the products of combustion passing over the 35 linings 14 and through the openings 21 therein, will necessarily descend passing through the opening 32 and up behind said rear lining 30 and out through the flue 5, the opening of the valve 34 creating the 40 necessary draft for the flow of the products of combustion from its source to its exit. It is understood the shelf or plate 20 is perforated or slotted to permit the products of combustion to pass therethrough.

45 From the foregoing it is obvious that I have designed a range or stove capable of being heated either by solid fuel or gas and which by the peculiar arrangement of flues or chambers may heat the oven uniformly 50 when using either, and that with the use of solid fuel or gas it is not necessary to remove or replace any parts of the structure. By connecting the valve 34 and the valve 41 with a common operating means, the valve 55 34 is always closed when the gas is turned off, and is always open when the gas is turned on. I show no valves controlling the ingress of air into the flues 28, but such may be used

if desired. This is a common expedient in stoves of this character and so forms no part 60 of the present invention.

What I claim is:—

1. In a gas stove, an oven, a flue, communicating with the oven at a point near the top thereof, a partition wall spaced a short 65 distance from the rear wall of the oven extending from the top thereof to a point near the bottom of the oven, vertical walls spaced from the side walls and arranged at the bottom to form an air circulating way and provided with slots in the main body thereof, a horizontally disposed partition wall spaced between the side partitions and provided with perforations through the body thereof, a hollow member at the rear of the oven, 70 gas burners communicating with said hollow member disposed within the space between the side partitions and the side walls of the oven and in the lower portions of said space, a gas inlet member communicating 75 with the hollow member, means for controlling the inflow of gas, a damper for controlling the outlet to the flue, a common control means for the gas inflow and for the damper, plate members secured to the outer side walls 80 of the oven, the same being formed to provide an air inlet way between said members and the side walls of the oven, said partitions being arranged in parallel relation and substantially in the same plane with the 85 burner members and the side walls of the oven having plural perforations providing communication from the space between said plate members to the space between the side partition members and the side walls of the 90 oven.

2. In a stove, in combination, an oven, an exhaust flue having communication therewith, a pair of heating units spaced apart substantially the width of the oven, gas supply means including means for equalizing the flow of gas to the respective units, means for regulating air circulation within the oven including a wall spaced from the rear wall of the oven and extending from its top 100 near to the bottom thereof, a horizontal partition, and side partitions the latter spaced from the side walls sufficiently to house the heating units and meeting the edges of the horizontal partition, said side partitions 105 arranged to afford communications between the side spaces and both the upper part of the oven and points below the horizontal partition.

LEE R. MOTHERWELL,
